DUCT SECTION FOR A VENTILATION TWIN-DUCT

Jorgen Holt, Naestved, Christian Videmark, Haslev, and
Palle Hein Christiansen, Naestved, Denmark, assignors
to Nordisk Ventilator Co., Aktieselskab, Naestved,
Denmark

Filed Dec. 8, 1972, Ser. No. 313,418

Claims priority, application Denmark June 9, 1972

Term of patent 14 years

Int. Cl. D23—04

U.S. Cl. D23—163

FIG.1

FIG.2

FIG.3

FIGS. 1 and 2 are opposite end perspective views of a duct section for a ventilation twin-duct showing our new design;

FIG. 3 is an exploded view of the duct section, the top half being omitted for convenience of illustration.

We claim:

The ornamental design for a duct section for a ventilation twin-duct, as shown and described.
